UNITED STATES PATENT OFFICE.

DAVID F. VAUGHAN, OF RIVERTON, NEW JERSEY.

ANTICREEPER FOR RAILROAD-RAILS.

1,113,516.

Specification of Letters Patent. Patented Oct. 13, 1914.

Application filed July 21, 1914. Serial No. 854,248.

To all whom it may concern:

Be it known that I, DAVID F. VAUGHAN, a citizen of the United States, residing at Riverton, in the county of Burlington and State of New Jersey, have invented certain new and useful improvements in Anticreepers for Railroad-Rails, of which the following is a specification.

My invention relates to improvements in anticreepers for railroad rails, of the type wherein a bar adapted to extend beneath the rail and having means on one end thereof adapted to engage one side of the rail base is employed in conjunction with a shoe adapted to engage the other side of the rail base and the bar.

The object of my invention is to provide an anticreeper of this type with a novel, simple and efficient means for clamping the shoe and the bar together and for securely holding the anticreeper in proper working position upon the rail. According to my invention I employ a locking member and insert it between a part of the bar and a part of the shoe and I construct and arrange the different parts so that the locking member will lock the bar and the shoe together and will be retained in place and parts of the anticreeper will be forced into gripping engagement with the rail by a part of the device constructed of spring metal and tending to resume a normal condition from which it was sprung. I prefer to form the locking member of spring metal and to construct and relate it to the other elements of the device so that it may be sprung from a normal condition to perform the spring function above mentioned, although the spring action need not be present in the locking member in the broad aspect of my invention as will hereinafter appear.

With this object in view, my invented anticreeper consists of the elements and the combinations of them hereinafter fully described and particularly claimed.

In the accompanying drawings, illustrating my invention: Figure 1 is a plan view of a portion of a railroad rail, a portion of a cross tie and one form of my improved anticreeper applied to the rail. Fig. 2 is an elevation of the parts shown in Fig. 1, as seen from a position looking at one end of the rail. Fig. 3 is a side view of the parts shown in Fig. 1. Fig. 4 is a side view of the parts shown in Fig. 1, showing the locking member out of locking position and above the

space into which it is forced when driven into locking position. Figs. 5, 6, 7 and 8 are views similar to Figs. 1, 2, 3 and 4, respectively, showing another form of my improved anticreeper.

Referring to the drawings, 2 designates a portion of a railroad cross tie and 3 a railroad rail of usual construction. The cross tie 2 forms a stationary part of the road bed which supports the rail 3 and over which the rail tends to creep under the well known conditions.

My improved anticreeper is supported by the rail base 4 and is of the following construction: Extending transversely beneath the rail 3 is a bar 5 having a hook 6 formed on one end thereof which is hooked over and engages one side of the rail base 4 and has its upper end 7 bent rearwardly to engage the top of the rail base rearwardly of the bar 5, as shown, for a purpose hereinafter explained. The other end of the bar 5 is provided with an upwardly-extending portion 8 and is adapted to engage a shoe 9 which embraces the side of the rail base 4 opposite to the side thereof engaged by the hook 6, and is constructed as clearly shown in the drawings. The upwardly-extending portion 8 of the bar 5 extends above the bottom of the rail 3 outwardly of one side thereof, and the shoe 9 has a portion 10 which extends over the bar 5 and between its upwardly-extending end portion 8 and the adjacent side of the rail, and the portion 8 of the bar 5 engaging the portion 10 of the shoe 9 retains the shoe in place upon the side of the rail base.

The shoe 9 extends downwardly, at 11, adjacent to the rearward face of the bar 5, and also, at 12, forwardly of the bar 5. The shoe 9 extends above and beneath the rail base 4 and thus embraces the adjacent side of the rail base both forwardly and rearwardly of the bar 5 while the portion 10 of the shoe 9 extending over the bar 5 does not extend beneath the rail base, permitting the bar 5 to lie close to the bottom of the rail throughout the width thereof. The lower portion of the rearward face of the bar 5 is engaged with the forward face of downwardly-extending portion 11 of the shoe 9, and the portion 11 has a projection 13 extending forwardly beneath the bar 5 and supporting the adjacent end thereof. The shoe 9 is provided with an outwardly-extending portion 14 having a groove 15

therein which faces the forward face of the upwardly-extending portion 8 of the bar 5. Located within the groove 15 is a locking member 16 which is inserted between the bar 5 and the projection 14 of the shoe 9. The locking member 16 is inserted into the top of the groove 15 and then driven downwardly into the position shown. Downward movement of the member 16 is limited by a shoulder or stop part 17 in the bottom of the groove 15; and, when the member 16 is in place, accidental upward displacement thereof is prevented by a projection 18 on the bar 5 and extending over the upper end of 15 the member 16.

Referring now only to Figs. 1, 2, 3 and 4, the locking member 16 is formed of spiral metal, and, in the normal condition thereof, is bowed, as shown in Fig. 4. When, however, the spring locking member 16 is driven into the position shown in Figs. 1, 2 and 3, it, in tending to resume its normal condition, exerts forward pressure against the shoe 9 and rearward pressure against the upwardly-extending end portion 8 of the bar 5 thereby forcing the lower portion of the rearward face of the bar 5 against the portion 11 of the shoe 9 and tending to twist the bar 5, and thus forcing the rearwardly bent end 7 of the hook 6 down upon the rail base 4. This action also tends to twist the shoe 9 by forcing its forward end downwardly upon the rail base and its rearward end upwardly against the bottom of the rail base, thereby forcing both the hook 6 and shoe 9 into gripping engagement with the rail. The spring locking member 16 is so shaped that its point of contact with the shoe 9 will be above the center of the member 16 to insure a greater pressure at the upper end of the member than at the lower end thereof, so that the greatest pressure against the bar 5 will be near the top of its upwardly-extending portion 8 to increase 40 the tendency of the spring locking member 16 to twist the bar and thus enhance the gripping action of the anticreeper against the rail base.

Referring now only to Figs. 5, 6, 7 and 8, the locking member 16 instead of being made in the form of a spring, is made in the form of a wedge, as shown; and the bar 5 is made of spring metal and thinner than that shown in Figs. 1 to 4. Further, in the normal condition of the bar 5, the upwardly-extending portion 8 thereof is inclined forwardly when the bar rests upon the projection 13 and the rearwardly bent end of the hook 6 rests upon the rail base 4 and before the wedge member 16 is driven into the groove 15, as shown in Fig. 8. When, however, the wedge member 16 is driven into the position shown in Figs. 5, 6 and 7, it forces the upper end of the upwardly-extending portion 8 of the bar 5 rearwardly, thereby twisting the bar 5

and springing it from its normal condition and causing it, in tending to resume its normal condition, to exert forward pressure against the wedge 16 and the portion 14 of the shoe 9 and rearward pressure against the portion 11 of the shoe 9 at the lower edge of the bar 5, thereby forcing the rearwardly bent end 7 of the hook 6 down upon the rail base 4 and the top of the bar 5 up against the bottom of the rail, so that the spring action of the bar 5 holds the anticreeper firmly in gripping engagement with the rail and causes the locking member 16 to lock the bar 5 and shoe 9 together.

In applying the anticreeper to the rail base 4, the shoe 9 is first applied to one side of the base 4 in the position shown. The hook 6 is then hooked over the other side of the rail base 4 and the bar 5 is brought into the position shown, in which one end of the bar is supported by its hook 6 resting on the rail base 4 and the other end of the bar 5 is supported by the projection 13 on the shoe 9. The locking member 16 is now inserted into the upper end of the groove 15 between the upwardly-extending portion 8 of the bar 5 and the outwardly-extending portion 14 of the shoe 9, and driven down into the position shown in Figs. 1, 2, 3, 5, 6 and 7. As the locking member 16 is driven into place, the spring action in the member 16 in the construction shown in Figs. 1 to 4, and the spring action in the bar 5, in the construction shown in Figs. 4 to 8, permit the upper end of the locking member 16 to pass below the projection 18 and cause the projection 18 to spring back over the top of the locking member 16 after it has been driven into place. The bottom of the projection 18 is beveled, as shown, to permit the locking member 16 to be forced upwardly and outwardly from its locking position, when it is desired to remove the anticreeper from the rail.

After the anticreeper has been applied to the rail it is adapted to grip the rail as hereinbefore described, and to engage the cross tie 2 and prevent the rail from creeping forwardly or in the direction of the arrow.

In the present form of embodiment of my invention, I extend the shoe 9 forwardly from the bar 5 so that the shoe alone will engage the cross tie 2 and maintain the bar 5 out of contact therewith. Should the rail attempt to creep forwardly, or in the direction of the arrow, forward movement of the shoe 9 and the adjacent end of the bar 5 will be prevented by the shoe 9 engaging the cross tie 2, and the rail 3 will carry the hooked end 6 of the bar 5 with it; and immediately upon the initial creeping movement of the rail 3, the bar 5 will tend to assume a diagonal position beneath the rail base 4, forcing the hooked end 6 inwardly against one side of the rail base and forcing

the upwardly extending portion 8 of the bar 5 inwardly against the shoe 9 and forcing the shoe 9 inwardly against the other side of the rail base, thus causing the anticreeper to increase its grip upon the rail and prevent it from creeping.

I claim:

1. The combination with a railroad rail having a base, and a stationary part of a road bed, of an anticreeper adapted to engage said stationary part and comprising a bar extending beneath the rail and provided with means to engage the rail base, a shoe engaging the rail base and a part of the bar, and a locking member inserted between a part of the bar and a part of the shoe, one element of the anticreeper being formed of spring metal and sprung from a normal condition and holding said member in place and forcing parts of the anticreeper against the rail in tending to resume said normal condition.

2. The combination with a railroad rail having a base, and a stationary part of a road bed, of an anticreeper adapted to engage said stationary part and comprising a bar extending beneath the rail and provided with means to engage the rail base, a shoe engaging the rail base and a part of the bar, and a spring locking member inserted between a part of the bar and a part of the shoe and sprung from a normal condition and forcing parts of the anticreeper against the rail in tending to resume said normal condition.

3. The combination with a railroad rail having a base, and a stationary part of a road bed, of an anticreeper adapted to engage said stationary part and comprising a bar extending beneath the rail and having a hook on one end thereof engaging one side of the rail base and having an upwardly-extending portion on the other end thereof adjacent to the other side of the rail base and extending above the bottom of the rail, a shoe engaging the rail base and a part of the bar, and a locking member inserted between a part of the bar and a part of the shoe, one element of the anticreeper being formed of spring metal and sprung from a normal condition and holding said member in place and forcing parts of the anticreeper against the rail in tending to resume said normal condition.

4. The combination with a railroad rail having a base, and a stationary part of a road bed, of an anticreeper adapted to engage said stationary part and comprising a bar extending beneath the rail and having a hook on one end thereof engaging one side of the rail base and having an upwardly-extending portion on the other end thereof adjacent to the other side of the rail base and extending above the bottom of the rail, a shoe engaging the rail base and a

part of the bar, and a spring locking member inserted between a part of the bar and a part of the shoe and sprung from a normal condition and forcing parts of the anticreeper against the rail in tending to resume said normal condition.

5. The combination with a railroad rail having a base, and a stationary part of a road bed, of an anticreeper adapted to engage said stationary part and comprising a bar extending beneath the rail and having a hook on one end thereof engaging one side of the rail base, and having an upwardly-extending portion on the other end thereof adjacent to the other side of the rail base and extending above the bottom of the rail, a shoe engaging the rail base and having a part extending between the upturned end of the bar and the rail, and a locking member inserted between a part of the shoe and the upturned end of the bar, one element of the anticreeper being formed of spring metal and sprung from a normal condition and holding said member in place and forcing parts of the anticreeper against the rail in tending to resume said normal condition.

6. The combination with a railroad rail having a base, and a stationary part of a road bed, of an anticreeper adapted to engage said stationary part and comprising a bar extending beneath the rail and having a hook on one end thereof engaging one side of the rail base and having an upwardly-extending portion on the other end thereof adjacent to the other side of the rail base and extending above the bottom of the rail, a shoe engaging the rail base and having a part extending between the upturned end of the bar and the rail, and a spring locking member inserted between a part of the shoe and the upturned end of the bar and sprung from a normal condition and forcing parts of the anticreeper against the rail in tending to resume said normal condition.

7. The combination with a railroad rail having a base, and a stationary part of a road bed, of an anticreeper adapted to engage said stationary part and comprising a bar extending beneath the rail and having a hook on one end thereof engaging one side of the rail base and having an upwardly-extending portion on the other end thereof adjacent to the other side of the rail base and extending above the bottom of the rail, the upper end of said hook having a bend therein extending laterally of the body of the bar, a shoe engaging the rail base and having a part extending between the upturned end of the bar and the rail, and a locking member inserted between a part of the shoe and the upturned end of the bar, one element of the anticreeper being formed of spring metal and sprung

from a normal condition and forcing said hook down upon the top of the rail base in tending to resume said normal condition.

8. The combination with a railroad rail having a base, and a stationary part of a road bed, of an anticreeper adapted to engage said stationary part and comprising a bar extending beneath the rail and having a hook on one end thereof engaging one side of the rail base and having an upwardly-extending portion on the other end thereof adjacent to the other side of the rail base and extending above the bottom of the rail, the upper end of said hook having a bend therein extending laterally of the body of the bar, a shoe engaging the rail base and having a part extending between the upturned end of the bar and the rail, and a spring locking member inserted between a part of the shoe and said upwardly-extending portion of the bar and sprung from a normal condition and forcing said hook down upon the top of the rail base in tending to resume said normal condition.

25 9. The combination with a railroad rail having a base, and a stationary part of a road bed, of an anticreeper adapted to engage said stationary part and comprising a bar extending beneath the rail and provided with means to engage the rail base, a shoe engaging the rail base and having a groove formed in a part thereof and facing one side of a part of the bar, and a locking member inserted into said groove between a part of the shoe and a part of the bar, one element of the anticreeper being formed of spring metal and sprung from a normal condition and holding said member in place and forcing parts of the anticreeper against the rail in tending to resume said normal condition.

10. The combination with a railroad rail having a base, and a stationary part of a road bed, of an anticreeper adapted to engage said stationary part and comprising a bar extending beneath the rail and provided with means to engage the rail base, a shoe engaging the rail base and having a groove formed in a part thereof and facing one side of a part of the bar, and a spring locking member inserted into said groove between a part of the shoe and a part of the bar and sprung from a normal condition and forcing parts of the anticreeper against the rail in tending to resume said normal condition.

11. The combination with a railroad rail having a base, and a stationary part of a road bed, of an anticreeper adapted to engage said stationary part and comprising a bar extending beneath the rail and provided with means to engage the rail base, a shoe engaging the rail base and having a groove formed in a part thereof and facing one side of a part of the bar, and a locking

member inserted into said groove between a part of the shoe and a part of the bar, said shoe having a stop part limiting movement of said member in one direction longitudinally of the groove, one element of the anticreeper being formed of spring metal and sprung from a normal condition and holding said member in place and forcing parts of the anticreeper against the rail in tending to resume said normal condition.

12. The combination with a railroad rail having a base, and a stationary part of a road bed, of an anticreeper adapted to engage said stationary part and comprising a bar extending beneath the rail and provided with means to engage the rail base, a shoe engaging the rail base and having a groove formed in a part thereof and facing one side of a part of the bar, and a locking member inserted into said groove between a part of the shoe and a part of the bar, said bar having a stop part preventing movement of said member in one direction longitudinally of the groove, one element of the anticreeper being formed of spring metal and sprung from a normal condition and holding said member in place and forcing parts of the anticreeper against the rail in tending to resume said normal condition.

13. The combination with a railroad rail having a base, and a stationary part of a road bed, of an anticreeper adapted to engage said stationary part and comprising a bar extending beneath the rail and provided with means to engage the rail base, a shoe engaging the rail base and having a groove formed in a part thereof and facing one side of a part of the bar, and a locking member inserted into said groove between a part of the shoe and a part of the bar, said shoe having a stop part limiting movement of said member in one direction longitudinally of the groove, said bar having a stop part preventing movement of said member in the reverse direction longitudinally of the groove, one element of the anticreeper being formed of spring metal and sprung from a normal condition and holding said member in place and forcing parts of the anticreeper against the rail in tending to resume said normal condition.

14. The combination with a railroad rail having a base, and a stationary part of a road bed, of an anticreeper adapted to engage said stationary part and comprising a bar extending beneath the rail and provided with means to engage the rail base, a shoe engaging the rail base and a part of the bar and having a projection extending beneath the bar and preventing downward displacement thereof, and a locking member inserted between a part of the bar and a part of the shoe, one element of the anticreeper being formed of spring metal

and sprung from a normal condition and holding said member in place and forcing parts of the anticreeper against the rail in tending to resume said normal condition.

- 5 15. The combination with a railroad rail having a base, and a stationary part of a road bed, of an anticreeper comprising a bar extending beneath the rail and having a hook on one end thereof engaging one 10 side of the rail base and having an upwardly extending portion on the other end thereof adjacent to the other side of the rail base and extending above the bottom of the rail, a shoe engaging the rail base and a part of 15 the bar, and a locking member inserted between a part of the bar and a part of the shoe, one element of the anticreeper being

formed of spring metal and sprung from a normal condition and holding said member in place and forcing parts of the anticreeper 20 against the rail in tending to resume said normal condition, said shoe extending forwardly from one end of the bar and being adapted to engage the stationary part of the road bed and maintain the other end 25 of the bar out of contact with said stationary part.

In testimony whereof I affix my signature in presence of two witnesses.

DAVID F. VAUGHAN.
